TOY VEHICLE PROJECTOR

Harvey W. La Branche, Palos Verdes Peninsula, Calif.,
assignor to Mattel, Inc., Hawthorne, Calif., a corpora-
tion of Delaware

Filed Jan. 20, 1970, Ser. No. 20,998

Term of patent 14 years

Int. Cl. D21—02

U.S. Cl. D34—15

FIG. 3

FIG. 1

FIG. 2

FIG. 4

FIG. 5

FIG. 6

FIG. 7

FIG. 1 is a perspective view of a toy vehicle projector showing my new design;

FIG. 2 is a right side view thereof;

FIG. 3 is a rear view thereof;

FIG. 4 is a left side view of FIG. 1 showing the projector in a loaded, or cocked position;

FIG. 5 is a top plan view thereof;

FIG. 6 is a front view thereof; and

FIG. 7 is a perspective view of another embodiment of the design shown as a dual unit.

I claim:

The ornamental design for a toy vehicle projector, as shown and described.
